UNITED STATES PATENT OFFICE.

ALFRED C. STEWART, OF LOS ANGELES, CALIFORNIA.

ECONOMIZING-THROTTLE FOR INTERNAL-COMBUSTION ENGINES.

983,654.

Specification of Letters Patent. Patented Feb. 7, 1911.

Application filed June 23, 1910. Serial No. 568,474.

To all whom it may concern:

Be it known that I, ALFRED C. STEWART, a citizen of the United States, residing at Los Angeles, in the county of Los Angeles and State of California, have invented a new and useful Economizing-Throttle for Internal-Combustion Engines, of which the following is a specification.

The main object of the present invention 10 is to provide means for admitting auxiliary air supply to the mixture in an internal combustion engine in such manner as to provide for maximum economy.

The invention is particularly intended to 15 provide for economizing in use of fuel by means operating in connection with the throttle in such manner that when the engine has been brought up to a given speed, with the throttle to a more or less wide open 20 condition, and the throttle is then moved back part way to closed position, auxiliary air will be admitted so as to dilute the mixture and economize in use of the fuel.

The invention is particularly intended for 25 application to automobiles. In running an automobile it is usual in speeding up the machine to open the throttle wide until the desired speed has been reached, and if at any time it is desired to ease up the speed, for 30 example, when obstructions, crossings, or turns are to be passed, or a slight down grade is reached, the throttle will be moved back part way toward closed position. In order to give high starting and pulling capacity it is usual to provide the engine with 35 an explosive mixture which is correspondingly richer than that requisite for maximum economy of fuel, and when the throttle is moved back in the manner above described, the efficiency of operation tends to remain 40 substantially the same as with the throttle wide open, the quality of the mixture being the same, but less being taken in at each stroke. By providing for admission of auxiliary air supply at such time, the mixture 45 is rendered more economical and the efficiency of the engine under such circumstances is correspondingly increased. Moreover, the admission of auxiliary air supply 50 increases the volume of charge admitted, thereby increasing the initial pressure which has a further effect on the increase of efficiency.

Other objects of the invention will appear 55 hereinafter.

The accompanying drawings illustrate the invention, and referring thereto:

Figure 1 is a side elevation of the throttle. Fig. 2 is a horizontal section through the throttle chamber. Fig. 3 is a transverse section on the line x^2-x^3 in Fig. 2. Fig. 4 is a side elevation showing a modified form of the invention.

1 designates the throttle chamber provided with the usual means 2 for attachment to a cylinder or manifold of an internal combustion engine and with the usual means 3 for attachment to a carburetor or means for supply of explosive mixture. The throttle valve 4 mounted in said throttle chamber is carried by a hollow stem 5 having a slot 6 communicating with the interior of the throttle chamber, preferably on the side toward the engine. Externally of the throttle chamber there is mounted on the 70 stem 5 an operating arm 7 connected to the usual controlling or operating means through a rod or other suitable device indicated at 8. Said operating arm 7 is loosely mounted on the stem 5 so as to be 75 capable of relative rotation thereon and is connected thereto through intermediate devices hereinafter described. The stem 5 also carries externally of the throttle chamber an arm or rocking member 10 fastened to stem 80 5 by pin or other means 13. An adjustable arm 11 is clamped, for example, by clamp means 12, on a fixed sleeve 9 on the throttle chamber. Rocking member 10 is provided 85 with a projection 15 for engaging the operating arm 7, and arm 11 is provided with a lug or projection 16 acting as a stop for the member 10. Member 10 is further provided 90 with a segment rack 17 engaged by a detent 18 which may be formed as a toothed segment pivoted on an arm 19 which is pivotally mounted on the fixed member or arm 11, a spring 20 being connected to the arm 11 and detent 18 to draw the detent 18 into engagement with the segment rack 17. Operating member 7 is provided with a projection or roller 21 adapted to engage the arm 19 to release the detent 18 from the segment rack, as hereinafter explained. A spring 22 100 connected to the members 10 and 11 tends to hold or move said member 10 in a direction to bring a part 10' thereon into position against the stop 16.

Valve stem 5 is closed at each end and, in addition to the slot 6, is provided with a 110

port 24 which coöperates with a port or opening 25 in the hub 26 on the arm 7, said ports 24 and 25 being normally out of register, but being moved into register under 5 certain conditions, as hereinafter described.

The operation of this form of the invention is as follows: The normal or inoperative position of the ports is shown in dotted lines in Fig. 1, the rocking member 10 being held 10 over by the spring 22, so that the stop portion 10' thereon is in contact with the stop 16 on the fixed member 11. At this time the controlling arm 7 may be in contact with the stop 15 on arm 10. The throttle 15 4 is closed and the ports 24 and 25 are out of register. In starting up the engine and in working under full power, the throttle is thrown up by drawing arm 7 over to the position shown in full lines in Fig. 1, said 20 arm engaging with projection 15 to move the rocking member 10 over at the same time. As the arm 7 begins to move, it passes away from the detent 18 allowing the same to come in contact with the segment rack 17 25 on the rocking member 10, said detent slipping over the teeth of the segment rack 17 in the rocking movement of the member 10, as above described, so as not to interfere with said movement. This operation of arm 30 7 opens the throttle, but as the rocking member 10 moves with the arm 7 no change takes place in the relative positions of the ports 24 and 25, so that the auxiliary air supply communication remains closed. If 35 now the arm 7 be moved back somewhat, so as to check the speed of the machine, by partially closing the throttle, the spring 22 tends to pull the arm 10 back to its normal position shown in dotted lines in Fig. 1, 40 but this motion is prevented by the detent 18, so that said arm is maintained in the position shown in full lines in Fig. 1. Consequently, the back movement of the handle 7 is accompanied by a relative movement 45 of the members 26 and 5 causing the port 25 to open communication from the outer air through the port 24 to the interior of the valve stem and through the opening 6 with the interior of the throttle chamber, prefer- 50 ably on the side toward the engine, so that auxiliary air is admitted to the mixture passing to the engine and as the handle is moved back farther to increase the throttling effect, the auxiliary air communication 55 is opened wider by registering of the ports 24 and 25, so as to increase the auxiliary air admission. By such admission of auxiliary air under the conditions stated, the economy or efficiency of operation of the engine is 60 increased, as above stated.

When it is necessary to stop the machine, it is requisite that the auxiliary air supply established as above described should be cut off and this is effected by the projection 65 or roll 21 on the arm or operating member

7 which, when the arm is moved clear back to normal position, as shown in dotted lines in Fig. 1, engages the arm 19 throwing it up to position shown in dotted lines, thereby releasing the detent 18 from the segment 70 rack 17 and allowing the spring 22 to draw the rocking member 10 back to normal position shown in dotted lines, in which the ports 24 and 25 are out of register.

The invention is not limited to the construction shown wherein the throttle valve itself is used as a means for admission of the auxiliary air supply, but, as shown in Fig. 4, may be applied in connection with an auxiliary hollow shaft sleeve 28 mounted 80 to turn in a chamber 29 connected to the throttle chamber 1', the throttle arm 7' in this case being connected by a link 30 to a lever 31 having an arm 32 provided with a projection 46. Another arm 34 mounted in fixed position is provided with a stop 45 for the arm 32 and said arm 32 is provided with a projection 46 for engaging with an operating arm 38 connected, as by means 49, so as to be operated or controlled for throttling the engine, said arm 38 having a sleeve 40 provided with a port 41 coöperating with a port 42 in the sleeve 28 communicating with the interior of the chamber 29. Fixed arm 34 is further provided with a pawl 44 95 engaging a segment rack 48 on rocking arm 32 and having a tail portion adapted to be engaged by a roller or projection 47 on the operating arm 38. The operation of this form of the invention is the same as that 100 above described, except that the admission of air is through the separate hollow sleeve 28 instead of through the stem of the throttle valve.

What I claim is:

1. In combination with the throttle of an internal combustion engine, and the controlling means therefor, auxiliary air supply means, and an operating connection between said air supply means and said throttle controlling means to open the auxiliary air supply in back movement of the said throttle controlling means for partially closing the throttle.

2. In combination with the throttle of an internal combustion engine, and the controlling means therefor, auxiliary air supply means, an operating connection between said air supply means and said throttle controlling means to open the auxiliary air supply 110 in back movement of the said throttle controlling means for partially closing the throttle, and means for closing the auxiliary air supply when the throttle is moved to closed position.

3. In combination with the throttle valve and throttle chamber of an internal combustion engine, an operating member connected to operate the throttle valve and having an auxiliary air supply port, a rocking member 130

having a passage communicating with said throttle chamber and having a port communicating with said passage and adapted to move into and out of communication with the port in the operating member, said rocking member being provided with means for engagement with said operating member, whereby operation of the operating member in closing the throttle will rock the rocking member, means for restoring said rocking member to normal position, and means for arresting the restoring movement of said rocking member in the back movement of the operating member to allow admission of air through the aforesaid ports.

4. The combination of a throttle chamber, a throttle valve therein, a stem for said valve having a port and a passage communicating with said chamber and with said port, a rocking member on said stem and moving with the stem and provided with a projection, a controlling arm mounted to move on

said stem, and to engage said projection for opening the throttle, a fixed member having a stop for the rocking member, a spring for moving said rocking member toward said stop to close the throttle, a detent mounted on said fixed member and engaging the rocking member to hold it from closing movement under the action of said spring, auxiliary air supply means operated by said controlling arm to establish air communication with the aforesaid port on relative movement of the rocking member and throttle, and means on the controlling arm engaging the detent to release the same from the rocking member.

In testimony whereof, I have hereunto set my hand at Los Angeles, California, this 14th day of June, 1910.

ALFRED C. STEWART.
